SPEAKER HOUSING

Kumi Yanagisawa and Masaharu Katayama, Saigyou,
Japan, assignors to Matsushita Electric Industrial Co.,
Ltd., Kadoma, Japan

Filed Apr. 6, 1972, Ser. No. 241,884

Term of patent 14 years

Int. Cl. D14—01

U.S. Cl. D26—14 G

FIG. 1

FIG. 2

FIG. 3

FIG. 1 is a front elevational view of a speaker housing showing our new design,

FIG. 2 is a bottom plan view, and

FIG. 3 is a rear and left side perspective view thereof. The right side view is identical with left side view.

We claim:

The ornamental design for a speaker housing, as shown and described.
